DIESTOCK

William O. Thewes, North Ridgeville, Ohio, assignor to The Ridge Tool Company, North Ridgeville, Ohio, a corporation of Ohio

Application April 11, 1933, Serial No. 665,533

6 Claims. (Cl. 10—124)

This invention relates to a ratchet tool or die stock assembly of that type wherein a toothed ratchet or drive ring adapted to receive the tool to be driven is mounted in an actuating frame 5 or barrel carrying a pawl for driving the ring. Tools of the type to which this invention relates are used principally as light duty thread-cutters and include in the assembly a set of die holders or heads which range in varying sizes to accommodate the particular diameter of the pipe or other article to be threaded and are each provided with a drive-ring engaging portion or drive barrel of standard external dimensions which detachably engages in the drive ring.

An object of the invention is to provide means of a simple and easily operated type for retaining a die-holder or analogous part in axially-removable association with the drive ring.

Another object of the invention is to provide an improved type of pawl mechanism for coacting with the teeth of the drive ring whereby back-lash or free running in a driving direction is reduced to a minimum without necessitating a reduction in width of the teeth of said ring.

The foregoing and other objects and advantages will become apparent in view of the following description taken in conjunction with the drawing, wherein:

Figure 1 is a view principally in axial section of a thread-cutting tool embodying the features of the invention;

Fig. 2 is a face view thereof;

Fig. 3 is a view in section taken in a plane normal to the axis of the tool;

Fig. 4 is a section taken on the line 4—4, Fig. 2.

Referring in detail to the drawing, 5 designates the actuating frame or barrel of the tool which is provided with a handle socket 6 adapted to receive a handle 7. Adjacent the handle is a pawl housing 8 in which a pawl assembly is mounted, said assembly comprising a pair of independently movable pawl teeth 9 and 9a, each of which is provided with a slot 10. These pawl teeth are mounted in a pawl housing or block 11 and retained against displacement by a pin 12 which passes through the slots 10. The pawl teeth are depressed against springs 13. The shank 11a of the pawl housing 11 is provided with a cap or head 14 having a direction-indicating arrow on the face thereof to indicate the driving direction of the ratchet. The pawl housing 11 is provided with a shouldered portion which has mounted thereon a spring 15 which serves

to normally urge the entire assembly towards ratchet-engaging position.

Mounted for free rotation in the barrel 5 is a driving ring 16 provided with teeth 17, said ring being held in assembled relation with respect to said barrel by means of a retainer ring 18. The teeth 17 of the driving ring 16 are practically of the straight cut type and are relatively broad and therefore rugged and capable of withstanding relatively heavy driving strains. These teeth, however, may be made of any suitable dimensions in accordance with the work the tool is required to perform. By referring to Fig. 3, it will be noted that the multiple-tooth construction of the pawl assembly reduces the free-running or back-lash movement of the barrel 5 in direct proportion to the number of teeth in the assembly. In the present instance, since two teeth are provided, the back-lash or free-running of the barrel 5 is reduced to fifty percent of what it would normally be were the pawl of the conventional one-tooth design. This is of considerable advantage in tools of this type where it is desirable to utilize a single pawl assembly acting at one point only on the periphery of the driving ring. Furthermore, in this construction the teeth of the pawl may be relatively rugged, or of ample width to withstand any reasonable work they may be called upon to perform.

Tools of the present type are usually provided with sets of die holders which range in varying sizes in accordance with work of varying diameter. One of the die holders is generally indicated at 20 and is provided with a drive barrel 20a which is of polygonal or flat sided formation to conform to the contour of the driving ring 16 and provides a driving engagement therebetween. The driving ring 16 is provided with an annular groove 21 in which a split ring 22 is inserted, said ring being adapted for resilient engagement in grooves 23 formed in the peripheral corners of the barrel 20a. These grooves preferably have tapered sides, and to save metal and lighten the tool for dies of relatively small diameter it is preferred to flatten or form a concave portion in each alternate corner of the barrel as at 23a. In the outer end of the holder 20 is the conventional thread-cutting chaser or die block 24. The free end of the barrel 20a is preferably tapered and of such length as to project slightly beyond the confines of the ring 16, as at 20b.

When it is desired to remove the die holder from the ring 16, it is only necessary to press on the projecting end 20b of the barrel 20a, where-

upon the ring 21 is spread or sprung outwardly thereby clearing the grooves 23 and permitting the holder to be easily removed axially outwardly. To substitute another block it is only necessary to push the latter in place in an obvious manner. Among the advantages of this type of retaining means for the holders 28 are that the latter can be applied from either side of the ratchet in an axial direction; it is not necessary to turn the holder to any particular point in order to register with a key way when it is desired to remove the holder, as in those types of tools wherein the holder has a splined engagement with the ring; and the parts may be economically manufactured.

It will be obvious that the die holder and die could be made integral and that other types of tools could be substituted for the thread-cutting dies and also for the die holder, and other limited structural modifications adopted without departing from the scope of the invention as defined by the appended claims.

I claim:

1. A die stock assembly comprising an actuating frame, a ratchet drive ring mounted for relative rotation in said frame, pawl mechanism associated with said frame and ring for rotating the latter, a tool-holder provided with a drive barrel which is inserted in and has a driving engagement with said ring, the ring and barrel being formed with coacting contiguous surfaces of polygonal formation, the periphery of the barrel being formed with an annular groove intersecting the corners of the polygon and the contiguous surface of the ring being formed with a complementary groove, and a split spring ring positioned in said grooves and serving to releasably hold the barrel against axial displacement with respect to said ring.
2. A die stock assembly comprising an actuating frame, a ratchet drive ring mounted for relative rotation in said frame, pawl mechanism associated with said frame and adapted to intermittently engage said ring, a die holder provided with a drive barrel adapted to be inserted in said ring, said ring and barrel being provided with coacting contiguous surfaces of polygonal formation to provide a driving engagement therebetween, the peripheral surface of said barrel and the contiguous surface of said ring being formed with complementary grooves, and a split retaining ring positioned in said grooves and serving to releasably retain the holder against axial displacement with respect to said ring, the end of said barrel being projected outwardly with respect to said ring to provide a thumb-engaging portion to facilitate removal of said holder.
3. In a die stock, an actuating handle frame, a ratchet ring mounted for relative rotation in said frame and having substantially straight-cut teeth, and pawl mechanism for initiating a driving

connection between the frame and said ring, said pawl mechanism including a spring-pressed housing block which is mounted for limited radial sliding movement in said frame adjacent said ring and a plurality of independently-movable spring-pressed pawls mounted for limited radial movement in said block and having tooth-engaging portions which face in the same direction, said pawls being of such width and spacing as to alternately mesh with each successive tooth of said ring.

4. In a die stock, an actuating handle frame, provided with a pawl housing, and pawl mechanism mounted in said housing, said pawl mechanism comprising a spring-pressed pawl housing block, a pair of independently movable pawl teeth mounted in said block and having tooth-engaging portions which face in the same direction, said teeth being provided with aligned openings, a retaining pin secured in the sides of the pawl block and extending through said openings to retain said pawls in said block, and a ratchet drive ring mounted in said frame and provided with substantially straight cut teeth adapted for engagement with said pawl teeth, the width and spacing of the pawl teeth with respect to the drive ring teeth being such as to cause alternate successive meshing of the pawl teeth with the drive ring teeth.

5. A die stock assembly comprising: an actuating frame, a drive ring mounted for relative rotation in said frame and having a polygonal-shaped opening therein, means associated with said frame and ring for rotating the latter, a tool holder having a drive barrel with a polygonal shaped periphery inserted in said opening to provide a driving engagement with said ring, the periphery of the barrel being formed with an annular groove having tapered cam-like side walls, and a split spring ring positioned in a groove formed in the inner periphery of the drive ring and resiliently engaging in the groove of said barrel whereby the latter is releasably held in the drive ring.

6. A die stock assembly comprising: an actuating frame, a drive ring mounted for relative rotation in said frame and having a polygonal-shaped opening therein, means associated with said frame and ring for rotating the latter, a tool holder provided with a drive barrel having a polygonal contour complementary to said drive ring opening, the inner periphery of the drive ring being formed with an annular groove and the said barrel being formed with a complementary peripheral groove, and a split spring ring positioned in the groove of the drive ring and releasably engaging in the groove of the drive barrel, said latter groove having tapered cam-like side walls to permit "thumb pressure" removal of said barrel.

WILLIAM O. THEWES.
